UNITED STATES PATENT OFFICE.

WILLIAM H. MAGEE, OF MOUNDSVILLE, WEST VIRGINIA, ASSIGNOR TO FOSTORIA GLASS COMPANY, OF MOUNDSVILLE, WEST VIRGINIA, A CORPORATION OF WEST VIRGINIA.

DESIGN FOR A GLASS GOBLET.

Application filed April 13, 1925. Serial No. 13,110. Term of patent 14 years.

To all whom it may concern:

Be it known that I, WILLIAM H. MAGEE, a citizen of the United States of America, and resident of Moundsville, county of Marshall, and State of West Virginia, have invented a new, original, and ornamental Design for a Glass Goblet, of which the following is a specification, reference being had to the accompanying drawings, in which—

The figures is a side elevation of a goblet, showing my new design.

I claim—

The ornamental design for a glass goblet, as shown.

WILLIAM H. MAGEE.
